BY

ATTORNEY.

UNITED STATES PATENT OFFICE.

JOBBY BELPEDIO, OF BRIDGEPORT, CONNECTICUT.

DESIGN FOR A TALKING-MACHINE CABINET.

55,448.

Specification for Design.

Patented June 15, 1920.

Application filed April 16, 1920. Serial No. 374,481. Term of patent 14 years.

To all whom it may concern:

Be it known that I, JOBBY BELPEDIO, a citizen of the United States, residing at Bridgeport, in the county of Fairfield and State of Connecticut, have invented a new, original and ornamental Design for a Talking-Machine Cabinet, of which the following is a specification, reference being had to the accompanying drawing, forming part thereof.

The figure is a perspective view of my new design.

I claim:

The ornamental design for a talking machine cabinet, as shown.

JOBBY BELPEDIO.
